RUFFLING AND STITCHING MACHINE

Frederic M. Card, Bridgeport, Conn., assignor to
The Singer Manufacturing Company, Elizabeth,
N. J., a corporation of New Jersey

Application December 20, 1938, Serial No. 246,779

19 Claims. (Cl. 112—132)

This invention relates to improvements in ruffling mechanisms for sewing machines and more particularly to ruffling mechanisms adapted to be brought into and thrown out of operation, 5 at the will of the operator, during the operation of the sewing machine. The primary object of the invention is to provide a ruffling mechanism for sewing machines capable of meeting high speed operation requirements.

10 The invention consists in the devices, combinations and arrangements of parts hereinafter described in connection with the accompanying drawings, which illustrate a preferred embodiment of the invention and in which:

15 Fig. 1 is a front elevation of the ruffler-blade actuating mechanism contained in a sewing machine bracket-arm head which is illustrated in vertical section. Fig. 2 is a top plan view, partly in horizontal section, of the ruffler-blade actuating mechanism. Fig. 3 represents a vertical section of the bracket-arm head of the machine, on substantially the line 3—3 of Fig. 1. Fig. 4 represents a longitudinal section, partly in front elevation, of the ruffler-blade carrier-arm. Fig. 5 20 represents a perspective view of the ruffler-blade and its carrier-foot. Fig. 6 represents a longitudinal vertical section of the sewing machine presser-foot. Fig. 7 represents a detail cross-sectional view of the slide-block and its path-controlling guideway.

The sewing machine referred to has the usual hollow bracket-arm 1, terminating at its free end in a head 2. Suitably journaled in the bracket-arm 1 is a horizontally disposed rotary actuating 25 shaft 3, upon one end of which is secured a counter-balanced crank-disk 4 provided with a crank-pin 5. The crank-pin 5 is connected by a link 6 to a needle-bar 7 carrying at its lower end a needle 8, said needle-bar being journaled for vertical 30 reciprocation in suitable bearings in the head 2.

Also journaled for endwise vertical movement in the head 2 is the usual spring-depressed presser-bar 9, to the lower end of which is secured the shank of a presser-foot 10. The presser-foot 10 35 has a sole-plate 11 bent to provide an upturned toe-portion 12, the sole-plate 11 having at the bend thereof a needle-aperture 13. Rising from the sole-plate 11, rearwardly of the needle-aperture 13, is a vertically-apertured boss 14 upon 40 which a cover-plate 15 is detachably secured by a screw 16. Vertically slidable in the aperture of the boss 14 is a stem 17 rising from an auxiliary pressure-shoe 18. The pressure-shoe 18 is disposed in a recess 19 which is provided in the under side of the sole-plate 11 rearwardly of the

needle-aperture 13 to extend lengthwise in the line of seam formation. Embracing the stem 17 is a spring 20 functioning to yieldingly depress the pressure-shoe 18 to an extent limited by a screw 21, said screw 21 entering a stem-recess 22 5 which provides sufficient clearance for limited vertical movement of the pressure-shoe. Any suitable form of looper or loop-taker mechanism may be employed for coaction with the needle 8 in the formation of stitches.

10 At the side of the crank-disk 4 opposite to the crank-pin 5 is an eccentric 24 which, as in the present case, may be integral with said crank-disk. Embracing the eccentric 24 is a strap 25 at the upper end of a generally vertically directed 15 pitman 26. The pitman 26 extends through a slot 27 in the bracket-arm head 4 and the lower end of said pitman pivotally carries a slide-block 28, provided with a lateral pivot-boss 28' which enters the apertured lower end of said pitman 26 and 20 is secured by a screw 29.

25 The block 28 is slidably disposed for reciprocation in a segmental groove or guideway 30 which determines the path of reciprocation of said slide-block. The guideway 30 is provided in an angularly adjustable segment-lever 31 disposed below the bracket-arm 1 and adjacent the head 2, said segment-lever being carried by a fulcrum-pin 32 which extends laterally from said lever. The fulcrum-pin 32 is journaled in a bushing 33 30 and is held therein by a screw 32', to provide for 35 rocking movements of the segment-lever 31 on an axis substantially parallel to the actuating shaft 3, said bushing 33 being secured by a screw 34 in an aperture in the bracket-arm head 2. The slide-block boss 28' also pivotally enters the 40 apertured rearward end of a link 35, of which the forward end is connected by the pivot-screw 36 to a crank-arm 37 clamped by a screw 38 upon a ruffler-blade actuating rock-shaft 39.

45 Extending rearwardly from the segment-lever 31 is an arm 49 to which is connected the lower end of a coil-spring 41 anchored at its upper end to a pin 42 extending from the bracket-arm head 2. The spring 41 functions to bias the segment-lever 31 yieldingly forwardly into engagement with an adjustable stop-screw 43 carried by the bracket-arm head 2. The radius of curvature of the segmental guideway 30 corresponds to the length of the link 35, whereby the pivotal axis 36 50 of said link is the center of curvature of the guideway 30 in one position of the segment-lever 31. This normal neutral position of the segment-lever is, in the present case, determined by the stop-screw 43 so that the slide-block 28 is recip- 55

located idly in the guideway 30 by the eccentric 24 and the ruffler-blade actuating rock-shaft 39 remains normally stationary.

In order to tilt the segment-lever 31 into a 5 position of the guideway 30 whereby the rock-shaft 39 is actuated, the arm 40 of said segment-lever is connected by a link 45 to a crank-arm 46 of a rock-shaft 47. The rock-shaft 47 is journaled in suitable bearings, as 48, at the rear side 10 of the bracket-arm 1 and has another crank-arm 49 suitably connected to a treadle or knee-shift (not shown). Disposed below the segment-lever arm 40 in position to be engaged by said arm is an adjustable stop-screw 50 threaded into a block 15 51 secured by screws 52 upon the head 2 at the rearward side thereof. The stop-screw 50 is opposed by a jam-screw 53 which is also threaded into the block 51 and serves to secure said stop-screw 50.

20 The ruffler-blade actuating rock-shaft 39 is horizontally disposed at the lower front side of the bracket-arm head 2 and is substantially parallel to the needle-reciprocating shaft 3, said rock-shaft 39 being journaled in a bearing-aperture 25 provided in a bracket-section 54 secured by screws 55 to the under side of the head 2. Secured upon one end of the rock-shaft 39 by a screw 56 is a lateral boss 57 of a carrier-arm 58 depending from the rock-shaft 39. The flattened lower end of the 30 carrier-arm 58 has a transverse bearing aperture 59 to pivotally receive a lateral bearing-boss 60 of an angular ruffler-blade carrying foot 61, said foot being pivotally secured to the carrier-arm 58 by a screw 62 threaded into the foot-boss 60. 35 Secured upon the pivotal carrier-foot 61, by screws 63, is a ruffler-blade 64 having a serrated free end underlying the toe 12 of the presser-foot 10. A spring 65, secured by a screw 66 to the carrier-arm 58, bears upon the carrier-foot 61 to yieldingly 40 depress the serrated end of the ruffler-blade 64.

The machine is preferably provided with the usual separator-blade 67 disposed below the ruffler-blade 64, the free end of the blade 67 also extending under the toe of the presser-foot 10 and 45 cooperating therewith to hold formed ruffles during the retracting movements of the ruffler-blade. The separator-blade 67 is suitably attached to a supporting plate 68 secured upon the machine cloth-plate indicated by a dot-dash line in Fig. 1 50 of the drawings, the separator-blade 67 being spaced from the cloth-plate. Suitable other attachments may also be employed dependent upon the character of the work to be performed, as for example, the folder 69 also secured to the supporting plate 68.

In the neutral position of the ruffler-blade actuating mechanism, the free end of the ruffler-blade 64 is tilted upwardly to provide work-clearance. To this end, the ruffler-blade carrier-foot 61 is 60 yieldingly engaged at the side thereof opposite the free end of the ruffler-blade 64 by the lower end of a carrier-foot tilting rod 70. The rod 70 is endwise slidably disposed in a bore 71 provided in and extending throughout the length of the carrier-arm 58. The rod 70 is shouldered between its ends, the reduced portion of said rod being embraced within the carrier-arm 58 by a spring 72 which yieldingly biases the rod 70 upwardly and away from the carrier-foot 61. Upward movement of the rod 70 under the action of the spring 72 is limited by a cross-pin 73 in the carrier-arm 58 and passing through a short slot 74 in the upper end of the rod 70.

The upper end of the rod 70 protrudes from the 75 carrier-arm 58 for engagement by the laterally

offset arm 75 at one end of a ruffler-blade tilting rock-shaft 76. The rock-shaft 76 is substantially parallel to the ruffler-blade actuating rock-shaft 39 and is journaled above the latter in a horizontal bearing-aperture in the bracket-section 54. At its 5 other end, the rock-shaft 76 carries a rearwardly extending crank-arm 77 provided at its free end with a lateral pin 78. The crank-arm pin 78 is embraced by the forked arm of a short lever 79 fulcrumed between its ends upon a pivot-screw 80 10 threaded into the head 2 for rocking movements of the lever 79 about an axis substantially parallel to the rock-shaft 76. The other arm of the lever 79 underlies a forwardly extending arm 81 of the segment-lever 31 for engagement by said arm 81. 15

The bracket-section 54 extends rearwardly under the machine bracket-arm 1 and, adjacent the bracket-arm head 2, is recessed to provide a substantially U-shaped lubricant-reservoir 82 which houses the inner end of the rock-shaft 39. 20 At its rearward end, the bracket-section 54 has a forwardly extending flange 83 which overhangs the rearward portion of the reservoir 82 to retain the lubricant within the reservoir when the machine head is tilted back for access to the mechanism below the cloth-plate. Disposed in the reservoir 82 for immersion in the lubricant contained therein is the lower end of a lubricant-conducting wick 84, of which the upper end is wrapped around the ends of the pitman 26 and the link 35 which 30 embraces the slide-block boss 28, thereby to provide for lubrication of the slide-block connection with said link and pitman.

Complemental to the bracket-section 54, as a housing for the ruffler-blade actuating connections 35 with the segment-lever 31, is a bracket-section 85 secured by screws 86 to the bracket-arm head 2. As applied to the machine, the bracket-sections 54 and 85 constitute extensions of the bracket-arm head 2, said bracket-sections 54 and 40 85 housing the actuating mechanism for the ruffler-blade carrier and also the ruffler-blade tilting-rod connections with said actuating mechanism. The rear wall of the bracket-section 85 is partly cut away to provide clearance for the segment-lever arm 40 and a guard-pad 87 of felt or other suitable lubricant-absorbent material is secured by a screw 88 to the inner face of said rear wall for sliding engagement by the segment-lever arm 40. The arrangement described provides for 45 detachment of the bracket-section 85 from the machine, without disturbing the ruffler-blade actuating connections or the reservoir-containing bracket-section 54. Therefore, while said connections are normally adequately housed, access 55 thereto may readily be had.

As will be understood from the foregoing description, the present stitching and ruffling mechanism is particularly adapted for at will producing any desired number of ruffles in the work during the stitching operation. Normally, the segment-lever 31 is yieldingly held by the spring 41 in its forwardly tilted or neutral position determined by the stop-screw 43. In this position of the segment-lever, the curved guideway 30 is concentric with the pivot-screw 36 and the slide-block 28 idly traverses said guideway, whereby the ruffler-blade 64 is normally stationary. The treadle-controlled rock-shaft 47 may be operated at will during the operation of the machine to 70 swing the slide-block controlling guideway 30 into the position thereof determined by the stop-screw 50, whereby the ruffler-blade actuating mechanism is rendered effective. It will therefore be understood that the ruffler-blade actu- 75

ating connections are dependent for effectiveness upon the path of reciprocation of the slide-block 28 determined by the position of the guideway 30.

At the lower end of the stroke of the pitman 5 26, the pivotal connection of said pitman with the slide-block 28 is substantially in alinement with the turning-axis of the segment-lever 31, the connections with the ruffler-blade carrier being such that the ruffler-blade 64 reaches its 10 extreme advanced position at the lower end of the stroke of the pitman 26. Consequently, the advance position of the ruffler-blade 64 is the same regardless of the length of stroke of said ruffler-blade determined by the extent of rearward tilting movement of the segment-lever 31 15 under treadle control.

From the foregoing, it will also be understood that the ruffler-blade, when idle, is in its advanced position. To provide the necessary work-clearance under the idle ruffler-blade 64, the serrated end of said ruffler-blade is slightly tilted upwardly by the engagement of the segment-lever arm 31 with the intermediate lever 79, thereby rocking the shaft 76 to depress the rod 70 20 lengthwise of the ruffler-blade carrier-arm 52. When the segment-lever 31 is angularly shifted into its effective position, the arm 31 thereof is moved away from the lever 79 to an extent permitting the spring 72 to raise the rod 70 sufficiently to clear the ruffler-blade carrier-foot 61. 25 Consequently, the serrated end of the ruffler-blade 64 is yieldingly depressed by the spring 65 whenever the ruffling mechanism is in effective operation.

30 Having thus set forth the nature of the invention, what I claim herein is:

1. In a ruffling and stitching machine, in combination, a rotary actuating shaft, a ruffler-blade carrier, a reciprocatory slide-block, operative 35 connections with said actuating shaft for reciprocating said slide-block, actuating connections with said ruffler-blade carrier dependent for effectiveness upon the path of reciprocation of said slide-block, a shiftable guideway determining the 40 path of reciprocation of said slide-block, and means controllable at will during the operation of the machine for shifting said guideway.

2. In a ruffling and stitching machine, in combination, a rotary actuating shaft, a ruffler-blade carrier, a reciprocatory slide-block, operative 45 connections with said actuating shaft for reciprocating said slide-block, actuating connections with said ruffler-blade carrier dependent for effectiveness upon the path of reciprocation of said 50 slide-block, an angularly shiftable guideway determining the path of reciprocation of said slide-block, and means controllable at will during the operation of the machine for angularly shifting said guideway.

55 3. In a ruffling and stitching machine, in combination, a rotary actuating shaft, a ruffler-blade carrier, a reciprocatory slide-block, operative connections with said actuating shaft for reciprocating said slide-block, actuating connections with said ruffler-blade carrier dependent for effectiveness upon the path of reciprocation of said 60 slide-block, a shiftable guideway determining the path of reciprocation of said slide-block, a stop defining a neutral position of said guideway 65 wherein said ruffler-blade actuating connections are rendered ineffective, and means controllable at will during the operation of the machine for shifting said guideway into and out of neutral positions thereof.

70 4. In a ruffling and stitching machine, in com-

bination, a rotary actuating shaft, a ruffler-blade carrier, a reciprocatory slide-block, operative connections with said actuating shaft for reciprocating said slide-block, actuating connections with said ruffler-blade carrier dependent for effectiveness upon the path of reciprocation of said slide-block, a shiftable guideway determining the path of reciprocation of said slide-block, a stop defining a normal neutral position of said guideway wherein said ruffler-blade actuating connections are rendered ineffective, means yieldingly biasing said guideway into said normal neutral position thereof, and manually operable means for shifting said guideway out of its neutral position.

15 5. In a ruffling and stitching machine, in combination, a rotary actuating shaft, a ruffler-blade carrier, a reciprocatory slide-block, operative connections with said actuating shaft for reciprocating said slide-block, actuating connections with said ruffler-blade carrier dependent for effectiveness upon the path of reciprocation of said slide-block, a shiftable guideway determining the path of reciprocation of said slide-block, opposed stops for limiting shifting movement of said 20 guideway, and means controllable at will during the operation of the machine for shifting said guideway from one to the other of said stops.

25 6. In a ruffling and stitching machine, in combination, a rotary actuating shaft, a ruffler-blade carrier, a reciprocatory slide-block, operative connections with said actuating shaft for reciprocating said slide-block, actuating connections with said ruffler-blade carrier dependent for effectiveness upon the path of reciprocation of said 30 slide-block, a shiftable guideway determining the path of reciprocation of said slide-block, a stop defining a normal neutral position of said guideway wherein said ruffler-blade actuating connections are rendered ineffective, means yieldingly biasing said guideway into said normal neutral position defined by said stop, an opposed stop defining a position of maximum effectiveness of said guideway, and manually operable means for shifting said guideway into its position of maximum effectiveness.

35 7. In a ruffling and stitching machine, in combination, a rotary actuating shaft, a ruffler-blade carrier, a reciprocatory slide-block, operative connections with said actuating shaft for reciprocating said slide-block, actuating connections with said ruffler-blade carrier dependent for effectiveness upon the path of reciprocation of said slide-block, an angularly shiftable guideway 40 determining the path of reciprocation of said slide-block, a stop defining a normal neutral position of said guideway wherein said ruffler-blade actuating connections are rendered ineffective, means yieldingly biasing said guideway into said normal neutral position defined by said stop, an opposed stop defining a position of maximum effectiveness of said guideway, and means operable at will during the operation of the machine for angularly shifting said guideway into its position of maximum effectiveness.

45 8. In a ruffling and stitching machine, in combination, a rotary actuating shaft, an eccentric carried by said shaft, a vibratory ruffler-blade carrier, a crank-arm operatively connected to vibrate said carrier, a normally stationary and 50 angularly-shiftable segmental guideway, a slide-block disposed for reciprocation in said guideway, a pitman embracing said eccentric and pivotally connected with said slide-block, a link pivotally connected at its opposite ends to said crank-arm.

and slide-block, said link corresponding in length to the radius of curvature of said segmental guideway, a stop determining a neutral position of said guideway in which said reciprocatory slide-block is ineffective to rock said crank-arm, means yieldingly biasing said guideway into engagement with said stop, and manually operable means for at will shifting said guideway into a position thereof determining a path of movement of said slide-block effective to actuate said ruffler-blade carrier.

9. In a ruffling and stitching machine, in combination, a vibratory ruffler-blade carrier-arm, a ruffler-blade carrying foot pivotally attached to said carrier-arm, a ruffler-blade foot tilting rod slidably mounted upon said carrier-arm for movement endwise of said arm, and means for moving said rod into and out of ruffler-blade foot tilting position thereof.

10. In a ruffling and stitching machine, in combination, a vibratory ruffler-blade carrier-arm, a ruffler-blade carrying foot pivotally attached to said carrier-arm, a ruffler-blade foot tilting rod slidably mounted upon said carrier-arm for movement endwise of said arm, operative connections normally effective to maintain said rod in a ruffler-blade foot tilting position thereof, and manually controlled means for retracting said rod.

11. In a ruffling and stitching machine, in combination, a vibratory ruffler-blade carrier-arm, a ruffler-blade carrying foot pivotally attached to said carrier-arm, normally ineffective actuating mechanism for said carrier-arm, a ruffler-blade foot tilting rod slidably mounted upon said carrier-arm for movement endwise of said arm, means normally effective for maintaining said rod in ruffler-blade foot tilting position, and means for rendering said carrier-arm actuating mechanism effective and simultaneously therewith for retracting said rod from ruffler-blade foot tilting position.

12. In a ruffling and stitching machine, in combination, a vibratory ruffler-blade carrier-arm, a ruffler-blade carrying foot pivotally attached to said carrier-arm, a ruffler-blade foot tilting rod slidably mounted upon said carrier-arm for movement endwise of said arm, a rock-shaft, a member carried by said rock-shaft for engagement with said rod thereby to tilt said ruffler-blade foot, and means for actuating said rock-shaft.

13. In a ruffling and stitching machine, in combination, a vibratory ruffler-blade carrier-arm, a ruffler-blade carrying foot pivotally attached to said carrier-arm, a ruffler-blade foot tilting rod slidably mounted upon said carrier-arm for movement endwise of said arm, a rock-shaft, a member carried by said rock-shaft for engagement with said rod, spring-biased connections for actuating said rock-shaft to tilt said ruffler-blade foot, manually operable means for controlling said spring-biased connections, and means for retracting said rod from ruffler-blade foot tilting position upon actuation of said manually operable means.

14. In a ruffling and stitching machine, in combination, a ruffler-blade actuating rock-shaft, means for actuating said rock-shaft, a vibratory arm carried by said rock-shaft, a ruffler-blade carrying foot pivotally attached to said arm, a ruffler-blade foot tilting rod slidably mounted upon said arm for movement endwise thereof, a tilting-rod actuating rock-shaft disposed substantially parallel to said ruffler-blade actuating

rock-shaft, means yieldingly biasing said tilting-rod actuating rock-shaft in one direction to maintain said rod in ruffler-blade foot tilting position, and manually controlled means for releasing said tilting-rod actuating rock-shaft from said biasing means.

15. In a ruffling and stitching machine, in combination, a rotary actuating shaft, a ruffler-blade actuating rock-shaft, a vibratory arm carried by said rock-shaft, a ruffler-blade carrying foot pivotally attached to said arm, a reciprocatory slide-block, operative connections with said actuating shaft for reciprocating said slide-block, actuating connections between said slide-block and said rock-shaft dependent for effectiveness upon the path of reciprocation of said slide-block, a shiftable guideway determining the path of reciprocation of said slide-block, means controllable at will during the operation of the machine for shifting said guideway, and ruffler-blade foot tilting connections dependent for effectiveness upon the slide-block influencing position of said guideway.

16. In a ruffling and stitching machine, in combination, a rotary actuating shaft, a ruffler-blade actuating rock-shaft, a vibratory arm carried by said rock-shaft, a ruffler-blade carrying foot pivotally attached to said arm, a reciprocatory slide-block, operative connections with said actuating shaft for reciprocating said slide-block, actuating connections between said slide-block and said rock-shaft dependent for effectiveness upon the path of reciprocation of said slide-block, a shiftable guideway determining the path of reciprocation of said slide-block, means controllable at will during the operation of the machine for shifting said guideway, a ruffler-blade foot tilting rod slidably mounted upon the arm of said ruffler-blade actuating rock-shaft for movement endwise of said arm means yieldingly biasing said rod into retracted position, and means dependent for effectiveness upon the slide-block influencing position of said guideway for maintaining said rod in ruffler-blade foot tilting position.

17. In a ruffling and stitching machine, in combination, a rotary actuating shaft, a ruffler-blade actuating rock-shaft, a vibratory arm carried by said rock-shaft, a ruffler-blade carrying foot pivotally attached to said arm, a reciprocatory slide-block, operative connections with said actuating shaft for reciprocating said slide-block, actuating connection between said slide-block and said rock-shaft dependent for effectiveness upon the path of reciprocation of said slide-block, a shiftable guideway determining the path of reciprocation of said slide-block, means controllable at will during the operation of the machine for shifting said guideway, a ruffler-blade foot tilting rod slidably mounted upon the arm of said ruffler-blade actuating rock-shaft for movement endwise of said arm, a tilting rod actuating rock-shaft disposed substantially parallel to said ruffler-blade actuating rock-shaft, and connections dependent for effectiveness upon the shifting of said guideway for rocking said tilting-rod actuating rock-shaft.

18. A ruffling and stitching machine having a frame including a bracket-arm terminating at one end in a head, a needle-bar journaled for reciprocation in said head, a rotary needle-reciprocating shaft journaled in said bracket-arm, a ruffler-blade actuating rock-shaft journaled at the front lower side of said head and disposed substantially parallel to said needle-reciprocating

shaft, a ruffler-blade carrying arm depending from said rock-shaft, a ruffler-blade carrying foot pivotally attached to said arm, a crank-arm carried by said rock-shaft, normally ineffective ruffler-blade actuating connections between said needle-reciprocating shaft and said crank-arm, manually operable means for at will bringing said ruffler-blade actuating connections into effective action, a bracket detachably secured upon said bracket-arm and together with said head housing said ruffler-blade actuating connections, and ruffler-blade tilting connections housed by said bracket.

19. A ruffling and stitching machine having a frame including a bracket-arm terminating at one end in a head, a needle-bar journaled for reciprocation in said head, a rotary needle-reciprocating shaft journaled in said bracket-arm, a primary bracket-section extending from said head

and provided with a lubricant reservoir, a ruffler-blade actuating rock-shaft extending into said reservoir, a vibratory arm carried by and depending from said rock-shaft, a ruffler-blade carried by said arm, a crank-arm carried by the end of said rock-shaft within said lubricant-reservoir, normally ineffective ruffler-blade actuating connections between said needle-reciprocating shaft and said rock-shaft crank-arm, manually operable means for at will bringing said ruffler-blade actuating connections into effective action, a complementary bracket-section detachably secured upon said bracket-arm, said complementary bracket-section together with said primary bracket-section and bracket-arm providing a housing for said actuating mechanism, and means extending into said reservoir for supplying lubricant to mechanism within said housing.

FREDERIC M. CARD.

CERTIFICATE OF CORRECTION.

Patent No. 2,169,579.

August 15, 1939.

FREDERIC M. CARD.

It is hereby certified that error appears in the printed specification of the above numbered patent requiring correction as follows: Page 1, second column, line 47, after the words "carried by" insert the aperatured head of a screw $\frac{1}{4}$ threaded into; page 4, second column, line 20, claim 15, for "fot" read foot; line 53, claim 17, for "connection" read connections; and that the said Letters Patent should be read with this correction therein that the same may conform to the record of the case in the Patent Office.

Signed and sealed this 19th day of September, A. D. 1939.

(Seal)

Henry Van Arsdale,
Acting Commissioner of Patents.
